UNITED STATES PATENT OFFICE.

H. CLAY BASCOM, OF TROY, TOBIAS S. HEISTER, OF LANSINGBURG, AND CYRUS A. HODGES, OF TROY, NEW YORK, ASSIGNORS TO SAID BASCOM.

DESIGN FOR A COOKING-STOVE.

SPECIFICATION forming part of Design No. 15 468, dated October 21 1884.

Application filed June 17 1884. Term of patent 7 years.

To all whom it may concern:

Be it known that we, H. CLAY BASCOM, a citizen of the United States, residing in the city of Troy, in the county of Rensselaer and State of New York, TOBIAS S. HEISTER, a citizen of the United States, residing in the village of Lansingburg, in said county and State, and CYRUS A. HODGES, a citizen of the United States, residing in said city of Troy, county of 5 Rensselaer, and State of New York, have jointly invented and produced a new and original Design for Cooking Stoves and Ranges, of which the following is a specification, reference being had to the accompanying print, cut, or 10 engraving representing our said new design.

This design embraces several new and distinct ornaments and combinations of ornaments and shapes which go to make up the whole design, as shown in the accompanying 15 illustration, and hereinafter specified.

One distinguishing feature of this design is the new and original compound ornament A, consisting of the central circular ornamentation, a, the two pairs of radiating, flaring, angular portions b and b', having incut-scroll form 20 and angular ornamentations, and the four intermediate radial flaring ornamental parts, c. Another distinctive part is the new and original compound ornament B, consisting of the 25 quadrant d, having scallop ornamentations along its arc, the two outer flaring three-lobed radial parts, e, and the three intervening trumpet-form radial ornamental parts, f. Another feature is the new and original compound ornament C, consisting of the lobed ornamented quadrant g, the two outer flaring two-lobed parts h, and the intermediate radial club-form parts, i. Another part is the shape and ornamentation of the door F, consisting of its rectangular border p, curved surface q, inclined ends r s t, four corner ornaments, B, and the central ornament, A, as shown. Another part is the shape and ornamentation of the door G, consisting of its rectangular border, curved panel surface, inclined ends, four corner ornaments, 30 C, and the middle ornament, D, consisting of the quadrants j, central ornament, k l, and connections m. Another part is the shape and ornamentation of the door or panel H, I, J, or 35 K, consisting of the rectangular border, curved panel surface, inclined ends, four corner ornaments, 40 C, and the middle ornament, E, substantially as set forth.

ments, C, and the middle ornament, E, consisting of the quadrants n, central ornament, o, and connections o'. The rear extension-plate has the lower curved and angular border, u, 55 the panel K, and a fan form ornament, B, consisting of the quadrant portion d and radial parts e and f.

The design for the front embraces the overhanging part M, door N, hearth O, and plate P, shaped and ornamented as shown.

The design for the legs Q consists of the front surface, r, inclined side surfaces, w, upper surface, x, and contracted lower portion, y, all shaped and ornamented as represented.

The entire design embraces the shape and ornamentation of the top, the front consisting of the parts M, N, O, and P, the side embracing the doors F G H I J and plate L, and the legs.

We claim as new—

1. In a design for a stove, the compound ornament A, consisting of the parts a, b, b', and c, shaped and ornamented as shown and described.

2. In a design for a stove, the compound ornament B, consisting of the parts d, e, e, and f, shaped and ornamented as described and shown.

3. In a design for a stove, the compound ornament C, consisting of the parts g, h, and i, shaped and ornamented as shown and described.

4. In a design for a stove, the shape and ornamentation of the door F, consisting of its rectangular border, curved panel-surface with end inclines, corner ornaments, B, and the middle ornament, A, substantially as shown and described.

5. In a design for a stove, the shape and ornamentation of the door G, consisting of its rectangular border, curved panel-surface with inclined ends, corner ornaments, C, and middle ornament, D, substantially as shown and described.

6. In a design for a stove, the shape and ornamentation of the door or panel H, I, J, or K, consisting of its rectangular border, curved panel-surface with inclined ends, corner ornaments, C, and middle ornament, E, substantially as set forth.

7. In a design for a stove or range, the shape

(COVER)

and ornamentation of the rear extension-plate, L, embracing the parts *u* K B, as shown and described.

8. In a design for a stove or range, the shape and ornamentation of the front, consisting of the parts M N O P, as shown and described.

9. In a design for a stove or range, the shape and ornamentation of the legs, consisting of the parts r w x y, as set forth.

10. A design for a cooking stove or range, consisting of the top, front, side, and legs, shaped and ornamented as set forth.

In testimony whereof we hereunto set our hands, in the presence of two subscribing witnesses, this 14th day of June, 1884.

H. CLAY BASCOM,
TOBIAS S. HEISTER,
CYRUS A. HODGES.
